F. F. BURTON.
TAKE-DOWN FIREARM.
APPLICATION FILED JULY 3, 1916.

1,195,777.

Patented Aug. 22, 1916.

UNITED STATES PATENT OFFICE.

FRANK F. BURTON, OF EAST HAVEN, CONNECTICUT, ASSIGNOR TO WINCHESTER
REPEATING ARMS CO., OF NEW HAVEN, CONNECTICUT, A CORPORATION.

TAKE-DOWN FIREARM.

1,195,777.

Specification of Letters Patent. Patented Aug. 22, 1916.

Application filed July 3, 1916. Serial No. 107,259.

To all whom it may concern:

Be it known that I, FRANK F. BURTON, a citizen of the United States, residing at East Haven, in the county of New Haven and 5 State of Connecticut, have invented a new and useful Improvement in Take-Down Firearms; and I do hereby declare the following, when taken in connection with the accompanying drawings and the characters 10 of reference marked thereon, to be a full, clear, and exact description of the same, and which said drawings constitute part of this application, and represent, in—

Figure 1 a broken view in right hand 15 side elevation of a gun constructed in accordance with my invention. Fig. 2 a broken view thereof partly in side elevation and partly in vertical, central longitudinal section. Fig. 3 a detached view in rear elevation of the gun-barrel and forearm, showing my improved take-up screw in place in the latter. Fig. 4 a detached view in front elevation of the receiver-extension. Fig. 5 a detached view in side elevation of the take-up bushing. Fig. 6 a corresponding view of the take-up screw. Fig. 7 a view in elevation of the slotted forward end of the take-up screw.

My invention relates to an improvement 30 in take-down firearms, the object being to provide simple, convenient and effective means for taking up the play or "shake" which may result from the wearing of the means by which the gun-barrel is removably 35 secured to the receiver of the arm.

With these ends in view, my invention consists in a take-down firearm provided with a take-up having certain details of construction as will be hereinafter described 40 and pointed out in the claims.

In carrying out my invention as herein shown, I employ a cylindrical take-up screw 2 exteriorly threaded throughout its length and formed at its rear or head end with a 45 flat bearing-face 3 having a kerf 4. The forward end of the said screw is formed, as shown, with a deep concentric chamber 5 and with a longitudinal slot 6, though this is not essential. The said screw is mounted in a 50 long internally threaded bushing 7 located in a circular chamber 8 formed in the rear end of the wooden forearm 9, the rear end of the bushing having a knurled band 10 embedded in the wood to prevent the bushing

from turning in the chamber 8. Prepara- 55 tory to inserting the take-up screw 2 into the bushing 7, the forward end of the screw, if slotted as shown, is very slightly spread apart so that when screwed into place it will be compressed and so held under tension 60 against rotation. The flat bearing-face 3 of the screw impinges against the flat forward face 11 of a receiver-extension 12 formed with a threaded opening 13 adapting it to be screwed over the reduced forward 65 end 14 of the receiver 15 which may be of any desired construction, and which, as shown, has an internally threaded opening 16 for the reception of the threaded shank 17 of the removable gun-barrel 18 which is 70 secured in place against rotation by means of a locking-screw 19 passed upward into the shoulder 20 of the barrel through an opening 21 leading upward from the lower face of the receiver-extension 12. 75

The forearm 9 is rigidly secured to the barrel by means of a screw 22 passing upward through it into a lug 23 extending into a recess 24 formed in the upper face of the rear portion of the forearm, the said screw 80 22 having its upper end reduced as at 25 to enter a hole 26 in the cylindrical portion 27 of the barrel. The said portion 27 of the barrel is provided for the application of the forearm-lock which comprises the lug 23 85 aforesaid and a band 28 with which the said lug is formed integral and from which it depends. The said band 28 is clamped upon the portion 27 of the barrel by means of a transverse clamping screw 29 passing 90 through the split rear end of the lug 23. The upper face of the band 28 is formed with a transversely arranged undercut groove 30 for the reception of a dovetail upon the lower face of the sight base of the 95 rear sight of the arm. As herein shown, the forward end of the tang 31 of the magazine is secured to the receiver-extension 12 by means of a screw 32 passing upward through the tang into a lug 33 projecting rearward 100 from the rear face of the receiver-extension 12. The butt-stock 34 extends forward to the rear face of the receiver-extension.

It will be observed that the forward end of the bushing 7 engages directly with the 105 rear end of the depending lug 23 which is clamped solidly upon the barrel by the screw 29. Under this construction the bush-

ing is held against forward thrusts imparted to it through the take-up screw 2.

In using the term "receiver" in the claims, I intend to cover, broadly, the receiver whether formed with a removable receiver-extension, or otherwise.

I claim:—

1. A take-down firearm characterized by having the rear end of its forearm provided 10 with a take-up screw mounted in a bushing located in the rear end of the forearm and adapted to engage with the forward end of the receiver for taking up wear in the connection between the same and the removable 15 gun-barrel.

2. A take-down firearm characterized by having the rear end of its forearm provided with a take-up screw mounted in a bushing located in the rear end of the forearm and 20 slotted to adapt it to be spread open so as to be frictionally held in place.

3. A take-down firearm characterized by having the rear end of its forearm provided with a take-up screw for co-action with the 25 forward portion of the receiver of the arm, the said screw being cylindrical and having its forward portion chambered and longi-

tudinally slotted to adapt it to be spread open so as to be frictionally held in place.

4. In a take-down firearm, the combination with the receiver thereof, of a gun-barrel removably secured thereto, a forearm, a bushing located in the rear end of the said forearm, and a cylindrical take-up screw mounted in the said bushing in position to 30 have its rear face engaged with the front face of the said receiver, and slotted throughout a portion of its length to adapt it to be spread open so as to be frictionally held against rotation in the said bushing. 35

5. In a take-down firearm, the combination with the receiver thereof, of a gun-barrel removably secured thereto, a forearm, a forearm-lock applied to the said gun-barrel and formed with a depending lug entering 40 the upper face of the said forearm, a bushing located in the forearm and having its forward end engaged with the said depending lug, and a cylindrical take-up screw mounted in the said bushing for engaging 45 with the receiver to take up the wear in the connection between the gun-barrel and the receiver.

FRANK F. BURTON.
